UNITED STATES PATENT OFFICE

FERDINAND F. WAECHTER AND LOUIS F. SNYDER, OF PHILADELPHIA, PENNSYLVANIA,
ASSIGNORS TO LINK-BELT COMPANY, OF CHICAGO, ILLINOIS, A CORPORATION OF
ILLINOIS

LOADER

Application filed December 22, 1927. Serial No. 241,756.

This invention relates to crawler loaders, and has for one object to provide a new and improved form of crawler loader wherein the boom may be tilted into the inoperative position, but wherein, during the time that the boom is in the operative position, it is held positively against tilting and constrained to a rectilinear movement only, toward and from the work, thus making available to force the digging end of the boom into the work, the entire weight of the boom applied along a line coincident with the axial line of the boom. Another object of the invention is to provide a boom wherein the center of gravity is above and to the rear of the pivot support at all times, so that when the lower or digging end of the boom is released automatically it swings itself into the inoperative position. Another object of this invention is to provide a light, rigid and durable thrust carrying means whereby the power applied on the supporting track or wheels which carry the truck may be directly applied to the digging end of the boom without the presence of loose or adjustable articulate connections, thereby promoting rigidity and providing a structure which does not tend to climb up over the work, but which, on the contrary, can be used as a positive digging structure of sufficient digging power to excavate solid materials and the like. Other objects will appear from time to time in the specification and claims. The invention is illustrated more or less diagrammatically in the accompanying drawings, wherein:

Figure 1 is a side elevation;
Figure 2 is a front elevation;
Figure 3 is a section along the line 3—3 of Figure 1;
Figure 4 is a section along the line 4—4 of Figure 1;
Figure 5 is a section along the line 5—5 of Figure 1;
Figure 6 is a detail side elevation of the lower boom track.

Like parts are indicated by like characters throughout the drawings and specification.

A is a truck platform and frame supported by means of a series of rollers A¹, A² on an endless propelling track A², which

track is driven by a sprocket A³ through a power transmission contained within the housing A⁴, A⁵ and controlled by a clutch A⁶ from the motor A⁷. A⁸ is a take-up sprocket whereby the tension in the track chain may be adjusted, and A⁹ are a plurality of idler rollers to support the return side of the track chains. Projecting upwardly from the platform A is a rigid supporting framework A¹⁰. The details of the truck track in supporting the framework are not essential, and of course might be varied as desired.

Located on the forward portion of the frame A¹⁰ are a pair of parallel forwardly and downwardly inclined tracks B. B¹, B² are flanged rollers or wheels adapted to travel along these tracks B and to carry in pivotal relation the boom B². B³, B⁴ are sheaves located one at the upper end of each of the tracks B. Cables B⁴ are dead ended adjacent to the sheaves B³, extend down around sheaves B⁵ on the axle B⁶ on which the boom is pivotally mounted, thence back up the sheaves B² and thence down to the drums B⁷, about which they are wound. These drums are both mounted on a housing shaft B⁸, which may be driven through a train of gears contained within the housing B⁹ from a hand wheel B¹⁰, though if desired, of course, a power means could be provided to drive the shaft B⁸. A brake, the details of which are not here shown, contained within the housing B⁹, is controlled by means of a brake lever B¹¹, to lock the shaft B⁸ in any desired position so that by manipulation of the shaft and two hoisting drums the rollers B¹ may be moved along the tracks B and held in position wherever desired.

The boom B² comprises the usual type of built-up structural girder. It has, at its lower or digging end, a shaft C upon which are mounted a plurality of sprockets C¹. This shaft C extends laterally at each end beyond the sides of the boom, and carries a plurality of spirally arranged paddles C², these paddles being arranged to feed inwardly toward the center of the boom on both sides, and being, therefore, arranged

about opposite spirals. At the upper end of the boom are sprockets C³, C³ mounted in adjustable bearings C⁴, there being take-up bolts C⁵ to adjust the position of these bearings and control the tension in the sprocket chains C⁶, C⁶ which travel around the sprockets at both ends of the boom and carry at spaced intervals therealong the excavating and conveying buckets C⁷. The chain is intended to operate in a counter-clockwise direction as seen in Figure 1 and the buckets travel in the direction as indicated by the arrow. C⁸ are side plates on opposed sides of the buckets extending over a point above the loading end of the boom to the discharge end.

Extending along the underside of the boom from a point beneath the discharge ends of the buckets down to a point immediately behind the loading end of the boom is a rigid fixed spill apron and bucket guide plate D. This apron protects the mechanism from spillage from the buckets and serves as a guide plate along which the buckets may travel on the return movement to the loading end of the boom. At the upper end of this guide plate D is a fixed chute D¹ which discharges into an adjustable chute D². This adjustable chute is mounted on the shaft D³, there being an adjustable link D⁴ whereby the angle of inclination of the chute D² may be varied. D⁵ is a worm wheel on the shaft D³ in mesh with a worm D⁶ on the worm shaft D⁷. A wheel D⁸ on the shaft may be rotated by means of a chain D⁹ to adjust the chute D² angularly to control the direction of discharge.

At the lower end the apron D terminates in a cutting edge or lip E having a removable reinforced angle E¹ extending across the machine behind and substantially in line with the excavating buckets. This cutting lip is reinforced by the angles E² and tied into the boom structure by the diagonal angles E³, E⁴ to give the necessary strength. E⁵, E⁵ are brackets extending downwardly from the underside of the boom and apron B. These brackets support a cross shaft E⁶ on either end of which are mounted rollers E⁷. These rollers are adapted to travel along the inclined track E⁸ on the quadrant E⁹. These tracks are parallel with the tracks B and that is the preferred arrangement, though it is obvious that much the same operation might be obtained if the tracks E⁸ were inclined with respect to the track B. E⁹, E⁹ are removable cover plates associated with the tracks E⁸ held in place by the screw E¹⁰ and pin E¹¹, the arrangement of the parts being such that when the pin E¹¹ is removed, the cover plate E⁹ can be moved about the point E¹⁰ far enough to allow the rollers E⁷ to be rotated away from the track when the boom swings about its pivot point on the shaft B⁶.

Under ordinary conditions this is not permitted,

ted, and the cover plates, when tightly held in place, totally prevent any swinging or rotation of the boom, and constrain it to a longitudinal movement parallel with its axis. The presence of these rollers and their association with these track elements adds greatly to the strength and rigidity of the structure, because, since the rollers are farther apart than the width of the boom, and since they are very close to the loading or excavating end of the boom, local change in resistance and local variations in the load on the boom are resisted by these rollers, thus greatly minimizing the torsional loads carried back by the boom to the supporting rollers B¹. X 80 is one of the axles or shafts of the vehicle.

Since it is frequently desirable with an excavator loader such as the one in question to dig out from a point below the support for the machinery, it is well to have the digging end of the boom extend some distance forward from the truck which carries the boom, but since it is desirable to have the boom discharge into wagons or cars which are located back of the truck, it is desirable that the rear end of the boom or the loading or conveying means associated with the rear end of the boom overhang a considerable distance so that the load may preferably be discharged into the middle of a truck or wagon body without interference from the crawler loader. Experience shows that these two requirements are best met by placing the pivot point of the boom at about the geometric longitudinal center of the boom. And since, when the loader is in operation it is always attended and always being watched, whereas when it is not in operation it is not being attended and watched, experience shows that it is well to have it remain in stable equilibrium in the inoperative position, and in instable equilibrium, if necessary, in the operative position. Therefore, if the boom and its associated parts are so proportioned that the center of gravity is to the rear and above the pivot point, if it is desired to collapse the boom this is done without any manipulation of the cables holding the rollers in position on the inclined track. All that is necessary is to remove the pin, slide the track cover plates to one side, and permit the boom to swing under the influence of gravity into the horizontal position, where the underside of the boom rests upon a stop F on the rear side of the frame. In order to control this swinging movement and limit the speed at which the boom rotates, as well as to make it convenient to again tilt the boom into the working position when it is desired, a cable F¹ is dead-ended on the boom at a point F² between its pivot point and its forward end extends about a sheave F³ on the supporting frame A and is wound about a drum F⁴ provided with a crank F⁵ whereby the operator may control the rate at which the cable is paid out, and

whereby the operator may tilt the boom into working position when desired.

The power to operate the excavating chain is applied to the shaft F⁵¹, which carries the sprocket wheels C², C³. At one end of this shaft is a drive sprocket F⁶. Over this drive sprocket travels a chain, one side of which extends over an idler sprocket F⁷ on the shaft B⁶, thence around a driving sprocket F⁸ associated with the gear case A⁵, thence back around an idler sprocket F⁹ and thence back around the sprocket F⁶. This chain is indicated at F¹⁰. In order to take up the slack in this chain and keep it tight at all positions of the boom, the idler sprocket F⁹ is carried on one arm to a bell crank lever F¹¹, the other arm of which carries a spring F¹², the other end of the spring being associated with the link F¹³ dead-ended on the boom. The spring is strong enough to hold the chain tight under all normal driving conditions, and as the boom is rotating or as the boom is longitudinally displaced, this spring always takes up the slack while at the same time permitting free tilting or longitudinal movement of the boom without in any way interfering with the driving function of the chain.

The use and operation of this invention are as follows—

The device of this application is intended primarily for use as a loader,—that is, for use in picking up material which may be on the ground or any other space, raising this material and discharging it into a bin, a vehicle body or other place. In the form shown herewith, the loader is mounted on an automotive vehicle and it is adapted to be driven into a pile of material, to raise it and discharge it into a suitable receptacle. It may also serve as a digging machine and may dig directly into the ground, and in certain positions of adjustment it may dig at a level below the level upon which the vehicle itself stands.

The device is shown in the figures in the operating position. In that position the boom is free to slide down until it contacts the ground or other surface from which the loading takes place. The boom is supported upon the two pairs of tracks. As these tracks are shown, they are substantially parallel with each other, but this is not essential. The boom is supported in a position above the ground by the main hoisting cable. This cable may be paid out so as to permit the boom to slide downward along the tracks and when this has happened, the digging end of the boom rests upon the ground, as shown in Figure 1. The device is then set in operation and the conveyor on the boom takes material from the ground, raises it along the boom and discharges it at the upper end through the chute and into any suitable receptacle. The gathering mechanism at the

sides of the digging end of the boom serves to draw material to the feed end of the conveyor so that it may be picked up by the conveyor. The machine as a whole is driven usually forward at a suitable speed so that as material is taken away, the machine is driven into the zone where it may collect further material. Under certain circumstances, the boom may be permitted to rest upon the ground with its entire weight, that is, the cable may be so paid out that it exerts no supporting effect. The weight of the boom and its associated parts then tends to dig into the ground and the machine may thus act as a digger, and may dig below the surface upon which the tread of the vehicle stands.

The boom as shown, is top heavy, and when free to rotate, it tips up out of the digging position. The lower tracks are channel shaped and the upper flanges are removable. Thus when it is desired to move the boom out of the digging position, these upper flanges of the lower track are unbolted or otherwise removed and the boom will then tilt so that the digging end is raised from the digging position and so that the boom then assumes a more or less horizontal position. This is a position for us when the machine is being driven from place to place and at other times when digging is taking place the small hand driven cable may be controlled to brake the tilting movement of the boom from the digging position so that it does not tilt downward too rapidly or too violently. By means of this cable also the amount of such tilting movement of the boom may be controlled and for certain purposes the boom may be tilted into an intermediate position between the full digging position and the full horizontal position.

The position of the boom along the tracks is controlled by the main hoisting cable. The boom may be permitted to slide down along the tracks in the position shown in Figure 1 or it may be raised above this position to the top of the track. It is free to slide up and down along the track in response to jolts or shocks which may come upon it during the loading operation and thus a cushioning effect is provided when the machine comes up against some obstacle and breakage or straining of parts is avoided. It is to be noted that this rearward movement of the boom in response to striking such obstacles is not a tilting movement, but is merely a sliding movement, the boom moving upward along the tracks. No tilting of the boom can occur until the upper flanges of the lower set of tracks have been removed and then the boom may be allowed to tilt.

When it is desired to bring the boom into the digging position from the inoperative position, the small hand cable is operated to tilt the boom. The position of the boom along

the tracks is regulated by the main hoisting cable. When the boom has been drawn down by the small hand cable until the lower rollers contact the lower tracks, the upper flanges of these tracks are put in operation and thereafter they resist tilting of the boom.

An important feature of the operation of the device is the rectilinear movement of the boom. As it has been expressed above when the device in working encounters an obstacle, the boom is mounted to permit upward yielding so as to avoid breakage and undue strains. This upward yielding movement is not a rotary movement. Thus when such yielding occurs, the boom moves upward without any rotating or tilting and when free to do so, moves downward again. The operator can, of course, raise the boom by operating the hoisting mechanism and when the boom is so raised, its motion is of course rectilinear and is without tilting. The boom may be raised by the operator when an obstacle is encountered on the ground or it may be lowered into a depression or in any way adjusted to suit the needs of the use to which it is put. If the boom is permitted to tilt as it raises, for example, over an obstacle, it will, as it comes down, come down on top of the obstacle, and thus it has a tendency to climb up on the pile of material. Where the movement is rectilinear, as in this device, there is no such climbing tendency. In the form of the invention here shown it is, therefore, an important feature that the movement of the boom, whether as a result of the control of the operator or as a result of contact with obstacles, is always rectilinear and there is no tilting or rotary motion of any sort.

We claim:

1. In a loader, a support, a loading boom supported from such support for movement therealong, such boom being top heavy and tending normally automatically to move out of the digging position.

2. In a loader, a support, a loading boom supported from such support for movement therealong, such boom being top heavy and tending normally automatically to move out of the digging position, and means adapted for retaining the boom in the digging position.

3. In a loader, an inclined support, a boom mounted on such inclined support for movement therealong, said boom being top heavy and tending normally to swing out of the digging position.

4. In a loader, an inclined support, a boom movably mounted on such inclined support, means for raising the boom along such support, said boom being top heavy and tending normally to swing out of the digging position.

5. In a loader, an inclined support, a boom movably mounted on such inclined support, means for raising the boom along such sup-

port, said boom being top heavy and tending normally to swing out of the digging position, in combination with selective means for holding it in the digging position.

6. In a loader, a plurality of tracks, a boom supported from such tracks, selective means for holding it generally in the digging position, the boom being free for limited movement in a plane parallel to the tracks when in the digging position. 70

7. In a loader, an automotive vehicle, a plurality of tracks, a boom supported from such tracks, said boom being top heavy and tending normally, when free to move, to move out of the digging position, and selective means for holding it generally in the digging position, the boom being free for limited movement in a plane parallel to the tracks when in the digging position. 75

8. In a loader, a plurality of series of tracks, a boom mounted for movement along such tracks in combination with hoisting means adapted to raise the boom bodily along the tracks, such boom being top heavy and tending, when free to move, to move out of the digging position. 80

9. In a loader, a plurality of series of tracks, a boom mounted for movement along such tracks in combination with hoisting means adapted to raise the boom bodily along the tracks, such boom being top heavy and tending, when free to move, to move out of the digging position together with means for holding it in the digging position. 85

10. In a loader, a plurality of series of tracks, each being substantially parallel to the other, a boom mounted for movement along such tracks, in combination with hoisting means adapted to raise the boom bodily along the tracks. 90

11. In a loader, a plurality of series of tracks, each being substantially parallel to the other, a boom mounted for movement along such tracks, in combination with hoisting means adapted to raise the boom bodily along the tracks, such boom being top heavy and tending, when free to move, to move out of the digging position, together with means for holding it in the digging position. 95

12. In a loader, an automotive vehicle, a plurality of series of tracks, each being substantially parallel to the other, a boom mounted for movement along such tracks, and provided with rollers adapted to move along such tracks, in combination with hoisting means adapted to raise the boom bodily along the tracks, such boom being top heavy and tending, when free to move, to move out of the digging position, together with means for holding it in the digging position. 100

13. A loader, an inclined support, a boom assembly mounted for tilting and other movement with relation to such support, a pivotal support for such boom assembly, and cable means for moving the boom along such 105

support, said cable means including a sheave mounted outside of the boom and fixed above the pivot point of such boom assembly.

14. In a loader, an automotive vehicle, a loading boom movably supported from such vehicle for tilting and sliding movement, such boom being top heavy and tending normally automatically to move out of the digging position, and selective means adapted for retaining the boom in the digging position.

15. In combination in a loader, a plurality of tracks, a boom, rollers upon said boom adapted to support the boom upon said tracks, one of said tracks formed to engage one of said rollers to hold the same in engagement with said track, whereby the boom is permitted to move along said tracks and held against tilting with relation thereto.

20 16. In combination in a loader, a plurality of series of tracks, a boom, rollers upon said boom adapted to support the boom upon said tracks, one of said tracks formed to engage one of said rollers to hold the same in engagement with said track, whereby the boom is permitted to move along said tracks and held against tilting with relation thereto.

25 17. In combination in a loader, a vehicle, a plurality of series of tracks on said vehicle, a boom, rollers upon said boom adapted to support the boom upon said tracks, one of said tracks provided with a member adapted to engage one of said rollers to hold the same in engagement with said track, whereby the boom is permitted to move along said tracks and held against tilting with relation thereto.

30 18. In combination in a loader, a vehicle, a plurality of series of tracks on said vehicle, a boom, rollers upon said boom adapted to support the boom upon said tracks, one of said tracks provided with a removable member adapted to engage one of said rollers to hold the same in engagement with said track whereby the boom is permitted to move along said tracks and held against tilting with relation thereto.

35 19. In combination in a loader, a vehicle, a plurality of tracks carried upon such vehicle, a boom tiltably mounted for movement along said tracks and provided with rollers contacting said tracks, said boom being provided at one end with a digging part, and means for receiving the thrust of digging, said means including additional rollers upon such boom and additional tracks upon such vehicle.

40 20. In combination in a loader, a vehicle, a plurality of tracks carried upon such vehicle, a boom tiltably mounted for movement along said tracks and provided with rollers contacting said tracks, said boom being provided at one end with a digging part, and means for receiving the thrust of digging, said means including additional rollers upon such boom and additional tracks upon such

vehicle, said last mentioned tracks formed to engage said last mentioned roller and to hold the same in register with said tracks, whereby sliding movement of the boom is permitted and tilting movement prevented. 70

Signed at Philadelphia, Pennsylvania, this 29th day of November, 1927.
